UNITED STATES PATENT OFFICE.

JOHN L. CASTILE, OF BOONE, IOWA.

TANK STAND.

Application filed August 8, 1921. Serial No. 490,624.

To all whom it may concern:

Be it known that I, JOHN L. CASTILE, citizen of the United States, residing at Boone, in the county of Boone and State of Iowa, ⁵ have invented certain new and useful Improvements in Tank Stands, of which the following is a specification.

This invention relates to an improved tank stand, being particularly designed for use ¹⁰ as an oil or fuel tank stand, and has as one of its principal objects to provide a device of this character whereby a single person may readily shift a tank to vertical position for filling the tank and may then return the ¹⁵ tank to horizontal position so that the contents of the tank may be drawn therefrom from time to time.

A further object of the invention is to provide a stand wherein it will not be necessary to remove the tank therefrom in order ²⁰ to fill the tank.

And the invention has as a still further object to provide a stand which will be characterized by structural simplicity and which, ²⁵ in practical use, will prove entirely efficient.

Other and incidental objects will appear hereinafter.

In the drawings:

Figure 1 is a perspective view showing a ³⁰ conventional tank in connection with my improved stand, the cradle of the stand being moved for supporting the tank in vertical position,

Figure 2 is a side elevation showing the ³⁵ tank in horizontal position,

Figure 3 is a section on the line 3—3 of Figure 2, looking in the direction of the arrows, and

Figure 4 is a detail perspective view showing the construction of the inner ends of the ⁴⁰ side bars of the shelf of the cradle of the stand.

Referring now more particularly to the drawings, I employ a base which is in the ⁴⁵ nature of a rectangular frame comprising corner posts 10 connected by upper and lower side and end bars 11 riveted or otherwise secured to each other as well as to the posts.

Mounted to rock upon the base is a cradle ⁵⁰ comprising side bars 12 connected at their ends by end bars 13 riveted or otherwise secured to the side bars. Extending through the upper ends of the posts at the rear end of the base and through the side bars 12 of ⁵⁵ the cradle near the rear end of the cradle, are rivets or other suitable fastening elements

¹⁴ swingingly connecting the cradle with the base and, as will be observed upon reference to Figure 3, the side bars of the cradle are formed to fit over the upper side bars of the ⁶⁰ base extending therealong. Thus, the cradle may be swung to rest in a horizontal position upon the base.

Mounted upon the cradle at its rear end is a laterally directed shelf comprising side bars 15 connected at their outer ends by a cross bar 16 riveted or otherwise secured to the side bars. At their inner ends, the side bars are, as shown in detail in Figure 4, slit to define lugs 17 and 18 fitting the inner ⁷⁰ ends of the side bars of the cradle and extending through said lugs and through the latter side bars are rivets or other suitable fastening devices rigidly securing the shelf to the cradle. Pivoted upon the side bars ⁷⁵ 15 of the shelf at their outer ends are legs 19 secured to said side bars by rivets or other approved fastening devices 20 and connecting said legs is a cross bar 21, the legs being foldable, as shown in Figure 2, to lie between ⁸⁰ the side bars of the shelf therebeneath.

Mounted upon the cradle at its ends are longitudinally bowed tank supporting members 22 bent at their ends to provide legs 23 upon the lower ends of which are formed lugs 24. ⁸⁵ The lugs of the forward member rest upon the side bars 12 of the cradle and are riveted thereto while the lugs of the rear member rest upon the lugs 18 of the side bars 15 of the shelf and are secured to the side bars of ⁹⁰ the cradle by the same rivets holding said latter lugs. Riveted or otherwise secured to the side bars of the cradle medially thereof, is a split retaining strap 25 the portions of which overlap and are connected by a bolt ⁹⁵ 26 and, as illustrated, this strap is designed to retain a tank, as conventionally illustrated at 27, upon the cradle, the tank abutting at its rear end against the shelf of the cradle and resting within the bowed supporting members 22 therefor. At its forward end the tank is provided with the usual spigot 28 as well as with a filling opening which is closed by a plug 29.

As will now be seen in view of the preceding description, when the cradle is disposed in normal horizontal position the cradle will support the tank 27 disposed horizontally upon the stand so that the contents of the tank may be readily withdrawn through the spigot 28. On the other hand, when the tank becomes empty the cradle may then, as ¹⁰⁰ ¹⁰⁵ ¹¹⁰

shown in Figure 1, be swung upwardly upon the stand to vertical position for shifting the tank to vertical position resting upon the shelf of the cradle, the legs 19 being extended to engage the ground or floor as the case may be for sustaining the weight of the tank. Accordingly, the plug 29 may then be removed and the tank conveniently filled when, after the plug has been replaced, the cradle may then be again swung downwardly upon the stand for disposing the tank in horizontal position. It will accordingly be seen that I provide a stand which may be readily manipulated by a single person for shifting the tank to a vertical position for filling the tank and returning the tank to a horizontal position so that the contents may be withdrawn therefrom.

Having thus described the invention, what is claimed as new is:

In a stand of the class described, a base constructed of angle iron comprising corner posts transverse and longitudinal bars rigidly secured together at the corners; a cradle similarly constructed of angle iron comprising two longitudinal bars and one transverse bar rigidly secured at one end of the cradle

in such a manner that it substantially coincides with the corresponding end of the base when the cradle is in a lowered position, the other end of the cradle being open; the flanges of the cradle bars being so situated that they rest upon and embrace three sides of the top in said position; journals for the cradle at the other end of said base, the open end of the cradle extending beyond the end of the base, a shelf positioned perpendicularly to the side bars of the cradle at the open end thereof, said shelf including side runners of angle iron and a transverse runner rigidly connecting said side runners, the side flanges of said side runners being secured to the open ends of the cradle bars and the inward flanges having their ends bent to form ledges and an arcuate tank support having legs with transverse feet resting upon the ledges and rigidly connected therewith, a second arcuate support at the closed end of said cradle similarly secured to the bars of the cradle, holding down means for a tank on said cradle and hinged legs at the free end of said shelf for supporting the cradle in upright position.

In testimony whereof I affix my signature.

JOHN L. CASTILE. [L. S.]
